CLAIM

The ornamental design for an absorbent article package, as shown and described.

DESCRIPTION

The file of this patent contains at least one drawing/photograph executed in color. Copies of this patent or patent application publication with color drawing(s) will be provided by the Office upon request and payment of the necessary fee.

FIG. 1 is a front, right and top perspective view of a first embodiment of an absorbent article package showing our new design;

FIG. 2 is a view of the front side of the package of FIG. 1; FIG. 3 is a view of the right side of the package of FIG. 1; FIG. 4 is a view of the back side of the package of FIG. 1; FIG. 5 is a view of the left side of the package of FIG. 1; FIG. 6 is a view of the top side of the package of FIG. 1; and FIG. 7 is a view of the bottom side of the package of FIG. 1.

FIG. 8 is a front, right and top perspective view of a second embodiment of an absorbent article package showing our new design;

FIG. 9 is a view of the front side of the package of FIG. 8; FIG. 10 is a view of the right side of the package of FIG. 8; FIG. 11 is a view of the back side of the package of FIG. 8; FIG. 12 is a view of the left side of the package of FIG. 8; FIG. 13 is a view of the top side of the package of FIG. 8; and,

FIG. 14 is a view of the bottom side of the package of FIG. 8.

The broken lines are shown for the purpose of illustrating parts of the article which form no part of the claimed design.
